UNITED STATES PATENT OFFICE.

THEODORE F. CONKLIN, OF FOND DU LAC, WISCONSIN.

ROAD-CART.

SPECIFICATION forming part of Letters Patent No. 271,223, dated January 30, 1883.

Application filed November 2, 1882. (No model.)

To all whom it may concern:

Be it known that I, THEODORE F. CONKLIN, a citizen of the United States, residing at Fond du Lac, in the county of Fond du Lac 5 and State of Wisconsin, have invented a new and useful Road-Cart, of which the following is a specification.

My invention relates to improvements in road-carts in which oscillating body-loops operate in conjunction with spiral springs and an equalizing tie-bar with the arms of the springs; and the objects of my improvement are, first, to neutralize the horizontal jerking action of the body of the vehicle; second, to provide an 10 easy vertical spring movement; third, to equalize the weight on the springs by automatically varying the leverage of the arms; and, lastly, to reduce the cost of material and construction in the springs of the vehicle, spiral springs 15 being the cheapest as well as the most flexible 20 for the purposes above stated. I attain these objects by the mechanism illustrated in the accompanying drawing, which is a perspective view of my invention with outline sketch of 25 body and parts of the vehicle of which it forms a part.

The spiral springs A are hung to the axle y of the vehicle by means of a bolt, d, through the core of the spring supported by clips e e, 30 fastened to the axle. The long arm A' of the spring produced from the top of the spiral extends backward and upward a convenient length, and moves with reference to the weight x backward and downward. The short end or 35 arm a of the spring rests against the forward face of the axle, y.

The body-loop B is formed of a bar bent in right angles at points opposite the outer corners or edges of the body or seat of the vehicle x, producing the arms or braces B' B', which are slightly curved, and extend downward and backward from the cart-body or seat x to the ends of the spring-arms A', and to which ends

they are hinged or pivoted. This body-loop B B' is attached to the rear end of the cart-body 45 x by straps, staples, eyebolts, or similar device, forming boxes b b, in which, through its bearings, the body-loop B turns or oscillates with the motion of the weight x.

The "equalizing-bar" C is laid across and affixed to the arms B' B' a proper distance from their respective ends, and (aside from its use as a tie) when extra weight of passengers and roughness of the road unusually depress the springs it meets and rests upon the spring-arms A' at points inside of the hinge n, and thus shortens the leverage and largely stiffens and strengthens the support of the springs. 50

The front of the cart-body is attached to the shafts or cross-bar g by means of any loop device playing loosely thereon. I show this as lettered f in the drawing, but claim no novelty or particular device for this front body-loop. 55

I claim as my invention and desire to secure by Letters Patent—

1. The combination, in a road-cart, of the spiral springs A A', attached to the axle y, of bolt d, and clips e e, with the body-loop B B', turning or oscillating in boxes b b, affixed to and supporting the cart-body or weight x, substantially as described. 60

2. The bar C, tying the braces B' B', and automatically impinging upon the portion of the spring-arm A' intermediate the spring-coil A' and hinged joint n, substantially as 70 shown, for the purpose specified.

3. The combination, in a road-cart, of the oscillating body-loop or braces B B' B', the spiral springs A A', the equalizing-bar C, and the cart-body x, axle y, and front body-loop, f, substantially as and for the purpose set forth. 75

THEODORE F. CONKLIN.
